UNITED STATES PATENT OFFICE

2,048,262

SELECTOR FOR CALCULATING MACHINES

Ernst Valfrid Gustafsson, Saint Essingen, and
Gustaf Hilarius Hellgren, Malmo, SwedenApplication November 14, 1933, Serial No. 698,005
In Sweden December 6, 1932

3 Claims. (CL 235—60)

This invention relates to selectors adapted to form a part of calculating machines of the ten-key type such as shown, for example, in Patent No. 1,930,475, granted October 17, 1933, on our prior application Ser. No. 327,587. The selector disclosed in that patent is claimed per se in our prior application Ser. No. 598,647, filed March 14, 1932, and the present invention relates to further developments in selectors of this general type.

- 10 An object of this invention is to provide improved selector constructions of the type in which numeral tongues are displaced by keys to serve as stops for calculator elements, the tongues being arranged in decimal order rows and having bent ends that engage the wall of a slotted or grid-like housing to retain the actuated tongues in displaced position. An object is to provide a selector of the character stated in which the bent ends of the tongues carry value designations for indicating the numerical quantity represented by the actuated numeral keys or in which the bent ends have the form of pointers which cooperate with numeral scales on the housing to indicate the set numerical quantity. More particularly, an object is to provide a selector including a housing having a slotted or grid-like wall, a selector carriage normally positioned laterally of the housing, rows of numeral tongues on the carriage, and key-actuated mechanism for displacing a tongue of successive rows and simultaneously moving the carriage into the housing, the displaced tongues entering slots in the housing and having bent ends which overlie the housing to retain the actuated tongues in displaced positions. A further object is to provide a selector of the character last stated, and in which the actuated tongues slide off of the slotted wall of the housing to return to normal position when the carriage is restored to its normal position laterally of the housing at the end of a calculating operation.

These and other objects and advantages of the invention will be apparent from the following specification when taken with the accompanying drawings that illustrate some preferred embodiments of the invention, and in which:

Figure 1 shows a vertical section through the selector showing one numeral key and a portion of a calculating or actuating member. Fig. 2 shows a selector and some parts of the frame of the machine in a front view, the front part of the housing of the machine having been left out. Figs. 3 and 3a show a stop tongue in a lateral and in a plan view. Fig. 4 shows the selector in the same manner as in Fig. 2 but in a different posi-

tion. Fig. 5 shows a selector in the same position as in Fig. 4 in which, however, the projecting end of the stop tongues has the form of a pointer. Figs. 6 and 7 show modifications of such a stop tongue provided with a pointer or pointers. Fig. 8 shows a vertical section through a portion of the housing of the calculating machine in which the covering plate with the slots shown in Fig. 1 has been replaced by rods. Fig. 9 shows some of these rods provided with strips on which the figure-indications are arranged. Fig. 10 shows the mounting and guiding of the rods.

In the following those parts only will be described more fully, which differ from the construction shown in our prior patent. The stop tongues 1 as shown in Figs. 1 and 8 project in the present case somewhat beyond the outer plate 2 of the selector and their ends 3 are bent at an angle and provided with figure-indications, see Figs. 2, 3, and 4. When a tongue is pressed out of the selector by means of a key 4 and the selector simultaneously is displaced, the front end of the tongue is introduced into a slot 5 in a covering plate 6 which is fixed to the housing 7 of the calculating machine. The covering plate 6 is set back in the housing and the space formed thereby is covered by a protecting plate 8 of glass, mica, or some similar transparent material. The dash-dotted lines of Fig. 1 show that a tongue 1a corresponding to the numerical value "5" has been pressed out by the numeral key and is situated in a slot 5 of the covering plate 6. On account of the angular form of this tongue this latter is prevented from falling back to its normal position.

Fig. 2 shows a selector in its normal initial position and Fig. 4 shows that the value 8685 has been introduced into the selector. All tongues, except said four in the first four vertical rows, remain invisible as also do the others which are situated behind the housing of the calculating machine.

According to a modification the tongues have at their projecting ends the form of a double pointer 9, 10, Fig. 6, or the form of a single pointer 11, Fig. 7. In this case the covering plate is provided with figure-indications 12, as disclosed in Fig. 5. This figure also shows in a similar manner to Fig. 4 that the numerical value 8685 has been introduced into the selector.

As further disclosed in Fig. 5 the pointers 11 are so arranged relative to the figure-indications that their points are in alignment with the figures. In case the tongue according to Fig. 6 is utilized, the points 9 and 10 will be situated on either side of the respective figure-indication. 55

In order to distinctly mark the figure-indications which come under consideration at the respective calculating operation it is preferred to differentiate the pointers and the figures by different colours. For instance, the figures may thus be made white on a black bottom and the pointers may be red.

Instead of using a covering plate having slots, rods 13 may be employed, such as shown in Figs. 8-10. These rods are fixed in a plate 14 which is mounted on brackets 15, 16 which by means of screws are securely fixed to the main frame 17 of the calculating machine. In order to guide the free ends of the rods the selector may be provided with an end plate 18 having corresponding holes 19, so that the rods pass through these holes when the selector is displaced. In this case, it is preferable to use tongues having figure-indications, but naturally small strips 20 having figure-indication may be mounted on the rods, such as indicated in Fig. 9, and then tongues such as illustrated in Figs. 6 and 7 are utilized.

What we claim is:—

1. In selector mechanism for calculating machines of the type having an outer casing provided with window openings, a housing having an outer wall positioned at a window opening of the calculating machine, said wall being provided with a plurality of horizontal slots extending inwardly from an open end of said housing, a carriage normally positioned laterally of the window opening and adapted to be displaced into the said housing from the open end thereof, a plurality

of stop tongues movably mounted on said carriage and arranged in a plurality of vertical columns, said tongues being arranged in rows in alignment with the several slots of said housing wall and each tongue having an outer indicator end normally positioned to the rear of the surface defined by said slotted wall, and means for selectively moving a desired tongue to project the indicating end thereof beyond the surface defined by said slotted wall, whereby the displacement of said carriage into said housing when one or more tongues are so moved will bring the indicator ends of the moved tongues into view at the window opening in front of the slotted wall of said selector housing. 5 10 15

2. A selector mechanism as claimed in claim 1, wherein the width of the indicator end of each tongue, as measured transversely of the direction 20 of movement of the tongues, is greater than the width of the slots in said housing wall.

3. A selector mechanism as claimed in claim 1, wherein the indicator end of each tongue is bent at an angle to the inner portion of the tongue, 25 the width of the bent indicator end portion being greater, as measured transversely of the direction of movement of the tongues, than the width of the slots in said housing wall, whereby said bent indicator ends will overlie a portion of said outer wall when projected beyond the same. 30

ERNST VALFRID GUSTAFSSON.
GUSTAF HILARIUS HELLGREN.
